TUBE END CLEANER

Filed Jan. 29, 1931

UNITED STATES PATENT OFFICE

1,924,682

TUBE END CLEANER

Frank F. Fisher, Detroit, Mich.

Application January 29, 1931. Serial No. 512,026

7 Claims. (Cl. 51—73)

This invention relates in general to means for cleaning tubular bodies, such as boiler tubes, wherein it is desired to obtain a clean and more or less polished outer surface at the end of the tube; and concerns itself more particularly with improvements in the device disclosed in my co-pending application, Serial Number 359,788, filed May 2, 1929.

Broadly, the invention in my co-pending application comprises guiding means in the form of a frame adapted to engage the outer periphery of a tube to be cleaned and suitably driven rotatable means mounted in the guiding means and provided with abrasive holders in the form of rocker arms which are spring loaded to normally hold the abrasive element in spaced relation to the periphery of the tube, and weighted so as to be actuated by the centrifugal force due to the rotation of the rotatable means. This action of the arms is effective to move the abrasive elements into wiping contact with the periphery of the tube end and exert a pressure thereon which is controlled or determined by the speed of operation of the rotatable means. Further, the abrasive elements therein are rigidly secured to the rocker arms.

In the present invention, I have provided novel means wherein the abrasive elements are resiliently secured to the rocker arms. This arrangement, I have found from experience, acts as a shock and vibration absorber and prevents transmission to the abrasive elements of the vibrations and shocks due to the operation of the device.

It is, therefore, an object of this invention to provide a device for cleaning tubes which embraces improved means for holding the abrasive in proper cutting position.

Another object of my present invention is to provide an improved support for the abrasive element in a tube cleaner which is designed to support the abrasive element in a flexible manner so that vibrations and shocks due to the operation of the machine will not be transmitted to the abrasive elements.

It is a further object of this invention to provide a support for the abrasive elements in a tube cleaning device, adapted to prevent the vibrations and shocks due to the operation of the device from being transmitted to the abrasive elements, thereby effecting a tube cleaner which is very efficient in operation and which will have a minimum of abrasive element breakages due to vibration of the device when operating.

It is also an object of the invention to provide an improved support for the abrasive element

which is so designed that the abrasive element is securely held against axial movement relative thereto, and which permits of an axial adjustment of the element in a quick and easy manner to compensate for wear.

In accordance with the general features of this invention, I provide a rocker arm having a weighted portion which is subject to the centrifugal forces created by the operation of my device, this arm being adapted for the pivotal securing to the tube cleaner frame of opposed clamping members which are arranged for clamping around the abrasive element. Resilient or rubber padding is disposed between the contact surfaces of the clamping members where they engage the abrasive element and the aforementioned arm.

A further feature of the invention resides in the provision of clamping members for gripping the abrasive element which are in threaded engagement with the element. The upper end of the abrasive element is countersunk or recessed for receiving a tool by means of which, when the clamping elements are loosened slightly, the abrasive element may be rotated a desired amount and moved axially by virtue of the threaded engagement with the clamping members to compensate for wear. With this arrangement all of the abrasive elements may be equally adjusted by turning each one a corresponding amount. Thus the necessity of measuring each element to obtain the correct adjustment is obviated.

The invention comprises the novel structure and combination of parts hereinafter described and more particularly pointed out and defined in the appended claims.

In the accompanying drawing which illustrates a preferred embodiment of this invention and in which similar reference numerals refer to similar features in the different views:

Figure 1 is an elevation showing the application of my present invention to a device as disclosed in my co-pending application;

Figure 2 is an enlarged fragmentary plan view partly in cross section showing the operative relationship between the centrifugally actuated arm and the means for resiliently mounting the abrasive element holder on the arm;

Figure 3 is an enlarged fragmentary sectional view through the abrasive element and clamp, showing the padding between the clamp and the abrasive element and arm, taken substantially on line III—III of Figure 1;

Figure 4 is a sectional view taken substantially on line IV—IV of Figure 2; and

Figure 5 is an enlarged fragmentary elevation of a modified form of my invention in which the abrasive element and clamping members are in threaded engagement.

As illustrative of my invention, I have shown in Figure 1 a pair of opposed clamping members 10 and 11 which are adapted to be clamped by means of clamping screws 12 around the stationary housing of suitable power means having a driving shaft 13. It is contemplated that the device of my invention may be connected to any type of power means, such, for example, as an electric motor or pneumatic motor. The clamping members 10 and 11 are provided with a plurality of circumferentially spaced bracket members 14 which project beyond the end of the rotatable shaft 13 of the power means and have secured at their outer ends by bolts 15 a guide member 16 which is provided with a central hub 17 to engage and fit the periphery of the tube, the end of which is to be cleaned. It will be noted that the hub 17 is concentric of the shaft 13 and serves to maintain the device in proper operating position.

Secured to the shaft 13 as by a key 18 is a transversely extending member 19 having forwardly projecting arms 20 disposed at its ends so as to revolve around the center line of the shaft 13, when it is rotated. The free end of each arm 20 is of reduced cross section as shown at 21 for receiving thereover a hub 22 to form a pivotal mounting for a rocker arm integral therewith. The inner end of the hub 22 abuts a flange 23 formed on the arm 20, the hub being secured against removal from the arm by means of a washer 24 which engages a shoulder 25 against which it is held by means of a suitable nut 26 and lock washer 27, suitable clearance being provided between the washer 24 and the outer end of the hub 22 to permit free movement on the hub about the contracted portion 21.

One element of the rocker arm is weighted as shown at 28 and the other element thereof is in the form of a lug 29 to which the abrasive element 30 is connected by means of a clamp.

The rocker arm is normally urged in a counter clockwise direction as viewed in Figure 1, by means of a coil spring 31 which surrounds the contracted portion 21 and is retained within a counterbore 32 at the inner end of the hub 22. One end of this spring engages a pin 33 fixedly secured in the flange 23 of the arm 20, and the other end engages the hub 22.

The abrasive element 30, which is preferably of circular cross section is supported on the lug 29 of the rocker arm by means of a pair of oppositely disposed clamping members 34 and 35 which are conformed to engage the surface of the abrasive element. These clamping members terminate at each end in integrally formed lugs 36 and 37 which are provided with apertures for receiving therethrough clamping bolts 38 and 39. The lugs 37 of the clamping members 34-35 are disposed on either side of the lug 29 and tightened around and against a resilient member 40 which is preferably of rubber although it is contemplated that other materials may be used with equal facility. This member is co-extensive with the inner surface of the clamping member with which it is associated. The lugs 37 are inwardly deflected to form portions 41 and 42 which extend over the upper and lower surfaces of the lug 29 and thus allow a slight rotational movement of the clamping members 34 and 35 together with the abrasive element 30 about the clamping bolt

39. With this arrangement, it will be obvious that the abrasive element 30 is not only resiliently mounted within the clamping members but that the entire clamping assembly and abrasive element are resiliently mounted relative to the arm 29, thereby preventing vibrations and shocks due to the operation of the device from being carried to the abrasive element with the advantageous result that the number of element breakages is very materially reduced.

In order to prevent flying particles of abrasive material and particles which have been removed from the pipe from flying into the surrounding space, and to prevent the operator of the device from being injured by these particles, a protective shield or guard 43 is secured to the bracket members 14 so as to completely surround the rotative elements of my device.

In the modified form of my invention, the clamping members 34 and 35 are threaded as shown at 44 for engagement with threads 45 formed on the abrasive element 30. The resilient pads 40 as in the preferred form of my invention are disposed between the abrasive element and the clamping members. The upper end of the abrasive element is recessed or countersunk as shown at 46 for receiving a tool by means of which the abrasive element may be rotated to effect axial movement thereof by virtue of the threaded engagement with the clamping members when the clamping bolts 38 and 39 are loosened slightly. Access to the recessed portion of the abrasive element is facilitated by providing an aperture 47 in the guard 43 which is in alignment with the recessed end of the abrasive element. By means of this arrangement the abrasive elements may be equally adjusted to compensate for wear by giving each element a corresponding turn. Thus, the necessity of measuring each element to adjust it to the proper length is obviated and much time is thereby saved.

Briefly the operation of my device is as follows: The device is applied to the end of the tube to be cleaned by passing the hub 17 over the tube end to such an extent that the abrasive elements will engage the peripheral portion thereof near the end to be cleaned. In this position the device is ready for operation and it will be noted that the abrasive elements will be out of engagement with the tube due to the action of the springs 31 upon the rocker arms. The power means is now started, whereupon the shaft 13 will be rotated and revolve the abrasive elements around the tube. As the power means comes up to speed and the rotative movement is accelerated, centrifugal force will actuate the counter-weights 28 so that they will move outwardly from the tube against the resistance of the spring 31 thereby bringing the inner face of the abrasive element into contact with the outer surface of the tube, the resulting pressure of the abrasive element on the tube being determined by the speed of rotation of the power means shaft 13. It is therefore obvious that this speed may be regulated to produce exactly the desired amount of pressure and the continued operation of the device will result in a wiping and polishing action of the abrasive on the surface of the tube to produce a very desirable and even cleaning as a result of being able to maintain an even pressure upon the abrasive element. Upon stopping the motor the abrasive elements 30 will be automatically moved out of engagement with the tube end due to the operation of the springs 31, since

when the rotational movement is suspended there will be no centrifugal force acting against the pressure of these springs. It is also obvious that this arrangement permits the device to be quickly 5 and easily used for cleaning tubes, without the necessity of having to make a lot of preliminary adjustments thereon.

The present invention, therefore, provides an improved tube end cleaner having novel means 10 for holding the abrasive element in operating position in which the vibration and shocks set up by the operation of the device will not be transmitted to the abrasive elements, a tube cleaner in which the abrasive element breakages are 15 greatly reduced; in which the support for the abrasive elements is so arranged that they will automatically adjust themselves to a proper cutting position, and in which novel means is provided for axially adjusting the abrasive elements 20 to compensate for wear.

Now, I desire it understood that, although I have illustrated and described in detail the preferred form of my invention, the invention is not to be thus limited but only in so far as defined 25 by the scope and spirit of the appended claims.

I claim as my invention:

1. A portable tube end polishing device comprising a rotatable structure having a plurality of members formed thereon and rotatable therewith, a pair of confronting clamping members connected to each of said members, an abrasive element disposed between and clamped by each 30 pair of clamping members, resilient means disposed between said first members and the adjacent clamping members, and means for actuating said clamps to grip said abrasive element and said resilient means.

2. A portable tube end polishing device comprising a rotatable structure having a plurality of members formed thereon and rotatable therewith, a pair of confronting clamping members pivotally connected to each of said members, an abrasive element disposed between each pair of 40 clamping members, means for actuating said clamping members, resilient means between said clamping members and the associated abrasive element, and means for limiting the pivotal movement of said clamping members and the abrasive element gripped thereby relative to their 45 associated first members.

3. A portable tube end polishing device comprising a rotatable structure having a plurality of members formed thereon and rotatable there- 50

with, a pair of confronting clamping members pivotally connected to each of said members, an abrasive element disposed between each pair of clamping members, means for actuating said clamping members, resilient means between said clamping members and the associated abrasive element, and flanges formed at the secured end of said clamping members for engaging said first member to limit the pivotal movement of said clamping members relative to their associated first members. 80

4. In a tube end polishing device the combination of an abrasive element with a support for said element, said support comprising clamping members, said clamping members and said element including threaded portions co-engaging in such a manner as to enable and gauge the axial movement of said element relative to said support. 85

5. In a tube end polishing device, a pair of clamping members and an abrasive element disposed between said members, said element and members having interfitting threads whereby the element may be moved axially a desired amount to compensate for wear. 90

6. A tube end polishing device comprising a rotatable structure having a plurality of members formed thereon and rotatable therewith, a pair of confronting clamping elements pivotally connected to each of said members, a stick of abrasive disposed between each pair of clamping elements, means to actuate said clamping elements, means to limit the pivotal movement of each pair of clamping elements relative to their associated member, and a yieldable material disposed between said clamping elements, and said latter means, and between said clamping elements and stick of abrasive. 100

7. A tube end polishing device comprising a rotatable structure having a plurality of members formed thereon and rotatable therewith, a pair of confronting clamping elements pivotally connected to each of said members, a stick of abrasive disposed between each pair of clamping elements, means to actuate said clamping elements, flanges formed at the pivoted ends of the clamping elements to engage said first members to limit the pivotal movement of the clamping elements relative thereto, and resilient means coextensive with the confronting surfaces of the clamping elements and extending between said flanges and first members. 110
